[57] CLAIM

The ornamental design for a magnifying glass, as shown
and described.

DESCRIPTION

FIG. 1 is a front elevational view of a magnifying glass
embodying my new design, the rear elevational view
being the same;

FIG. 2 is the right side elevational view thereof, the left
side elevational view being the same;

FIG. 3 is a bottom plan view thereof; and,

FIG. 4 is a top plan view thereof.
